UNITED STATES PATENT OFFICE

NORRIS E. GOODRICH, OF BATTLE CREEK, MICHIGAN, ASSIGNOR TO SANITARIUM EQUIPMENT COMPANY, OF BATTLE CREEK, MICHIGAN

THERAPEUTIC LAMP

Application filed February 6, 1929. Serial No. 337,814.

The main object of this invention is to provide a therapeutic lamp adapted to produce ultra-violet and also infra-red rays.

A further object is to provide a lamp having these advantages which is very simple and economical in structure and easily manipulated.

Objects relating to details and economies of my invention will appear from the description to follow. The invention is defined and pointed out in the claims.

A structure which is a preferred embodiment of my invention is illustrated in the accompanying drawing, in which:

15 Fig. 1 is a perspective view of my improved therapeutic lamp.

Fig. 2 is a diagrammatic view illustrating the connections for the parts, the lamp being shown in one adjustment.

20 Fig. 3 is a diagrammatic view with the lamp shown in another adjustment.

In the embodiment illustrated, the reflector 1 is tiltably mounted upon a standard 2. The details of this mounting are not, 25 however, illustrated as they form no part of this invention.

The reflector 1 is provided with a segmental guard 3 disposed across its lower end and adjacent its front edge to retain any débris that 30 may fall from the electrodes.

The reflector is provided with a ventilating opening 4 on its upper side.

I provide an arc lamp, the electrodes 5 of which project through openings 6 in the 35 sides of the reflector so that the arc is central of the lamp. These electrodes are mounted for manual adjustment, the adjusting means being indicated at 7, the details however not being illustrated as they form no 40 part of this invention.

I also provide a resistance coil 8 which is wound upon a suitable core and is connected in series with the electrodes. This resistance coil is of such character that it 45 becomes heated to a dull red, producing the infra-red rays. The resistance coil is arranged in the upper part of the lamp above the electrodes. If it is desired to use the infra-ray unit or element exclusively, the electrodes may be shorted as indicated in Fig. 3.

My improved lamp is well adapted for producing infra-red rays as well as rays resulting from the arc lamp; at the same time the lamp is very economical to produce and easily manipulated.

I have illustrated and described my improvements in an embodiment which I have found very practical. I have not attempted to illustrate and describe other embodiments or adaptations as it is believed that this disclosure will enable those skilled in the art to embody or adapt my improvements as may be desired.

Having thus described my invention, what I claim as new and desire to secure by Letters Patent, is:

1. In a therapeutic lamp, the combination of a reflector provided with a ventilating opening in its upper side located centrally with its upper edge substantially spaced from the edge of the reflector, a pair of electrodes disposed in cooperative relation within said reflector centrally below said ventilating opening, and a segmental guard disposed transversely across the bottom of the reflector in a plane perpendicular to the axis of the reflector, in advance of a similar plane passing through the electrodes.

2. In a therapeutic lamp, the combination of a reflector, an arc lamp operatively associated with said reflector and comprising electrodes projecting into the reflector, and a transversely disposed segmental guard extending across the bottom of the reflector in a plane perpendicular to the axis of the reflector, in advance of a similar plane passing through the electrodes.

In witness whereof I have hereunto set my hand.

NORRIS E. GOODRICH.
